(57) **CLAIM**

The ornamental design for a “coupling interface,” as shown and described.

DESCRIPTION

FIG. 1 is a left, front perspective view of a coupling interface.

FIG. 2 is a left side view of the coupling interface of FIG. 1.

FIG. 3 is a rear view of the coupling interface of FIG. 1; and, FIG. 4 is a front view of the coupling interface of FIG. 1. The top view and bottom view of the coupling interface of FIG. 1 are the same as the left side view shown in FIG. 2. The right side view of the coupling interface of FIG. 1 is a mirror of the left side view shown in FIG. 2.

The features shown in broken lines form no part of the claimed design.
